UNITED STATES PATENT OFFICE.

ROBERT LESLIE BELLHOUSE, OF MANCHESTER, ENGLAND, ASSIGNOR TO THE FINE COTTON SPINNERS AND DOUBLERS ASSOCIATION LIMITED, OF MANCHESTER, ENGLAND.

COMBING MACHINE.

Application filed February 6, 1922. Serial No. 534,535.

To all whom it may concern:

Be it known that I, ROBERT LESLIE BELLHOUSE, a British subject, residing at Manchester, county of Lancaster, England, have 5 invented certain new and useful Improvements in Combing Machines, of which the following is a specification.

This invention relates to improvements in combing machines of the Nasmith type and 10 more particularly to the weighting of the top detaching rollers thereof,

The top detaching roller in a combing machine of the Nasmith type has very commonly been weighted by a weight suspended 15 on a rod or wire attached to one end of a bell crank lever mounted on a shaft, the other end of the bell crank lever being connected by a rod or wire to a lug on the underside of the lever or hook carrying the detaching roller. This form of weighting is 20 objectionable as the bell crank lever rocking on its shaft sets up friction and is difficult to lubricate and the effective weight on the rollers is consequently very variable.

25 It has also been proposed to depend a weight from a chain connected at one end to the lever, and passing therefrom horizontally over a guide pulley. This form of weighting is also objectionable on account of 30 the friction between the pulley and its spindle.

Another construction employs a spring connected to each lever and anchored to the beam. The objection to this is a variation 35 in tension applied to each roller in every head of the machine.

The invention consists essentially in suspending the weights directly from the pivoted and oscillating levers which carry the 40 top leather detaching rollers of Nasmith combers as distinct from suspending the weight through the intermediary of a bell crank lever or over a guide pulley.

The invention will be fully described 45 with reference to the accompanying drawings.

Fig. 1. is a diagrammatic side elevation

showing one method of applying the invention over the beam.

Fig. 2. is a diagrammatic side elevation 50 showing another method of applying the invention at the side of the beam.

The lever A which carries the top leather detaching roller B is of the ordinary construction pivoted at a and operates in the 55 ordinary way.

It is provided with a notched lug a' nearly vertically below the centre of the roller B preferably on its upper side to engage the weight wire or cord C. The weight 60 W is suspended by the wire, rod or cord C either above the beam D as in Fig. 1, or to one side of it as in Fig. 2. In the latter case the weight W' is caused to hang clear of the beam by the wire or cord C' passing through a second wire or cord e which holds the weight away from contact with the beam D. The other end of the wire or cord is attached to some fixed part of the machine, a convenient position being an arm E fixed immovably to the stud e on which the bell crank 65 lever had previously been pivoted.

The invention does away with all existing bell crank levers or other moving levers and is practically frictionless.

75 What I claim as my invention and desire to protect by Letters Patent is:—

In a Nasmith comber the combination with the top detaching roller of a lever which carries the detaching roller, a notched lug on said lever below the detaching roller, a weight suspender engaging with and suspended from said lug, a guide wire engaging the suspender, a fixed arm to which the guide wire is affixed and a weight attached 80 to the lower end of the suspender.

85 In testimony whereof I have hereunto set my hand in presence of two subscribing witnesses this 20th day of January, 1922.

ROBERT LESLIE BELLHOUSE.

Witnesses:

J. OWDEN O'BRIEN,
GEORGE H. O'BRIEN.
